UNITED STATES PATENT OFFICE.

GEORGE W. SCHODDE, OF NEW YORK, N. Y., ASSIGNOR TO BRAYMAN MANUFACTURING COMPANY, OF NEW YORK, N. Y., A CORPORATION OF NEW YORK.

GUTTER.

No. 888,753.

Specification of Letters Patent.

Patented May 26, 1908.

Application filed July 14, 1906. Serial No. 326,172.

To all whom it may concern:

Be it known that I, GEORGE W. SCHODDE, a citizen of the United States, residing at the city of New York, borough of Manhattan, in the county and State of New York, have invented certain new and useful Improvements in Gutters, of which the following is a full, clear, and exact specification.

My invention relates to improvements in plumbing, and the same has for its object more particularly to provide a simple, efficient and reliable sectional gutter, which may be easily and permanently secured in the floor of stables, lofts, and other structures.

Further said invention has for its object to provide a gutter in which the opposing or adjoining ends may be secured together in such a manner as to produce a permanent and perfectly water-tight joint.

To the attainment of the aforesaid objects and ends my invention consists in the novel details of construction and in the combination, connection and arrangement of parts hereinafter more fully described, and then pointed out in the claims.

In the accompanying drawings forming part of this specification, wherein like numerals of reference indicate like parts, Figure 1 is a top view, partly broken away, showing one form 30 of a gutter constructed according to and embodying my said invention; Fig. 2 is a longitudinal section of the same, taken on the line 2—2 of Fig. 1, and Fig. 3 is a transverse section taken on the line 3—3 in the direction of 35 the arrow Fig. 1.

In said drawings 5, 5 denote correspondingly shaped trough sections which may be made of any suitable material and substantially U-shaped in cross-section. Each of 40 said trough-sections 5, 5 is provided at one end with an offset portion 6 having upon its inner surface an inwardly extending rim or bead 7, and at its opposite end a flange portion 8 which projects laterally from said 45 trough section 5, and longitudinally beyond the end thereof, thus providing an inclosed or covered end portion 9 of the trough intermediate which and said offset portion 8 the offset portion 6 of the adjoining trough section 5 is adapted to extend, and be firmly secured therein by calking the same with a quantity of oakum or analogous material 10, and a quantity of lead 11.

The portion of the trough section 5 at the 55 junction of its intermediate portion with the

offset portion 6 is recessed upon its inner surface at 12 to receive one end of a connecting section 13 which is firmly secured to said offset portion 6 against a shoulder 14 by screws 15 15. The said connecting section being 60 conformed to the inner surface of said trough section to which it is secured and its free end adapted to contact with the inclosed end 9 of the adjoining trough section and thereby providing a smooth unbroken surface. 65

Along the inner surfaces of the longitudinal edges of the trough sections 5 5 are provided shoulders 16 16 adapted to support the conformed cover plates 17 17 which are curved transversely and provided with apertures 18 18.

It is to be noted that an important feature of my improved gutter construction is that it permits of the entire gutter system being adjusted in position in the flooring, whether 75 the same be wood, cement or stone, before the trough sections are secured together, and that this may be easily done from the interior of the gutter prior to securing the connecting sections 13 in position therein. 80

Without limiting myself to the details of construction which may be varied within the scope of the invention as defined by the claims, what I claim and desire to secure by Letters Patent is:

1. A gutter comprising a plurality of trough sections each having an offset portion at one end, and a flange section inclosing its other end adapted to receive the offset portion of an adjoining trough section, and 85 packing material interposed between the inner surface of said offset portion, and the outer surface of said inclosed trough end, substantially as specified.

2. A gutter comprising a plurality of trough sections each having an offset portion at one end, and a flange section about its other end adapted to receive the offset portion of an adjoining trough section, packing material interposed between the inner surface of said offset portion and the outer surface of said inclosed trough end, and perforated plates for said trough sections, substantially as specified. 100

3. A gutter comprising a plurality of trough sections each having an offset portion at one end, and a flange section extending longitudinally along its other end and adapted to receive the offset portion of an adjoining trough section, and packing material in- 110

- terposed between the inner surface of said offset portion and the outer surface of the inclosed trough end, substantially as specified.
4. A gutter comprising a plurality of trough sections each having an offset portion at one end, and a flange section extending longitudinally along its other end and adapted to receive the offset portion of an adjoining trough section, packing material interposed between the inner surface of said offset portion and the outer surface of the inclosed trough end, and perforated cover plates for said trough sections, substantially as specified.
5. A gutter comprising a plurality of trough sections each having an offset portion at one end, and a flange section extending outwardly from and longitudinally of said trough section at its other end adapted to receive the offset portion of an adjoining trough section, and packing material interposed between the inner surface of said offset portion and the outer surface of the inclosed trough end therein, substantially as specified.
6. A gutter comprising a plurality of trough sections each having an offset portion at one end, a transverse recess upon the inner surface of said offset portion, and a flange section extending outwardly from and longitudinally of said trough at its other end adapted to receive the offset portion of an adjoining trough section, packing material interposed between the inner surface of said offset portion and the outer surface of the inclosed trough end therein, and a connecting section secured in the recess in one of said trough sections, and its other end abutting against the inclosed end of the other trough section, substantially as specified.
7. A gutter comprising a plurality of trough sections each having an offset portion

at one end, a transverse recess upon the inner surface of said offset portion, and a flange section extending outwardly from and longitudinally of said trough at its other end adapted to receive the offset portion of an adjoining trough section, packing material interposed between the inner surface of said offset portion and the outer surface of the inclosed trough end therein, a connecting section secured in the recess in one of said trough sections, and its other end abutting against the inclosed end of the other trough section, and perforated plates for said trough sections, substantially as specified.

8. A gutter comprising a plurality of trough sections each provided along its longitudinal edges with shoulders, and having an offset portion at one end, a transverse recess upon the inner surface of said offset portion, and a flange section extending outwardly from and longitudinally of said trough at its other end adapted to receive the offset portion of an adjoining trough section, packing material interposed between the inner surface of said offset portion and the outer surface of the inclosed trough end therein, a connecting section secured in the recess in one of said trough sections, and its other end abutting against the inclosed end of the other trough section, and perforated plates for said trough sections conforming in outline to said trough sections and the offset portions thereof, substantially as specified.

Signed at the city of New York, in the county and State of New York, this ninth day of July, nineteen hundred and six.

GEORGE W. SCHODDE.
